PULL TAB FOR TEAR STRIP OPENER

Donald V. Hanlon, Webster Groves, and James M. Kilpatrick, St. Louis, Mo., assignors to Container Corporation of America, Chicago, Ill., a corporation of Delaware

Filed Mar. 14, 1967, Ser. No. 6,218

Term of patent 14 years

(Cl. D58—26)

FIG. 1 is a top plan view of a pull tab for a tear strip opener showing our new design;

FIG. 2 is a side elevational view thereof;

FIG. 3 is a bottom plan view thereof;

FIG. 4 is an end elevational view taken from the top of FIG. 1; and

FIG. 5 is an end elevational view taken from the bottom of FIG. 1.

We claim:

The ornamental design for a pull tab for tear strip opener, substantially as shown.
